UNITED STATES PATENT OFFICE

ARCHIE D. ROBINSON, OF WESTFIELD, MASSACHUSETTS

GRINDING-WHEEL ADAPTER

Application filed June 4, 1928. Serial No. 282,819.

This invention relates to an adapter, which is intended to be placed in the bore of a wheel, such as a grinding wheel for example, for the purpose of centralizing 5 therein an arbor, having a diameter smaller than that of said bore.

The manufacturer of grinding wheels is faced with the problem that a wheel, of any given size, may be used on arbors of widely 10 varying diameters. To avoid making each size of wheel with a plurality of different bores to fit all possible conditions which may arise, he standardizes the bore and furnishes the user with a device to adapt this standard 15 bore to the customer's arbor.

The adapter for such use must be simple and inexpensive in construction. At the same time, it must also be simple to install and yet effective for its purpose, which is 20 to centralize the arbor in the bore of the wheel, while the holding flanges on the arbor are being clamped against the side faces of the wheel.

The object of the invention is to provide 25 an adapter for the purpose described, which may be made up from thin sheet metal by methods adapted for quantity production manufacture at low unit cost, and which will effectively centralize the arbor in the bore 30 of the wheel while the latter is being clamped between the holding flanges.

The invention also has for an object to provide an adapter for the purpose described, one only of which is required for each 35 wheel. The one adapter may be located entirely within the bore of the grinding wheel and will serve its purpose equally well regardless of the width of the wheel,—being effective for the narrowest as well as the 40 widest and all intermediate widths of wheels over the usual range.

The invention also has for an object the provision of an adapter for the purpose set 45 forth, which is so constructed that the one adapter will serve to centralize arbors of various diameters within a given range; thereby making it unnecessary to provide an adapter for every size of arbor to be used. 50 These and other objects will appear in

the following description and will be pointed out in the appended claim.

The invention will be disclosed with reference to the accompanying drawings, in which:

Fig. 1 is a sectional elevational view showing an adapter, embodying my invention, applied to a grinding wheel;

Fig. 2 is a fragmentary cross sectional view taken on the line 2—2 of Fig. 1;

Fig. 3 is a developed view of the blank from which one of the adapters is made;

Fig. 4 is an end view of one of the adapters; and

Figs. 5, 6 and 7 are sectional elevational views showing the three sizes of adapters needed to cover the entire range of arbors which may be used with one grinding wheel.

Referring to these drawings, the adapter is preferably made up from flat thin sheet metal. Blanks, such as that shown in Fig. 3, may be stamped from such metal, forming a strip 10 from one edge of which a plurality of fingers 11 extend. These fingers are bent backwardly relatively to the strip 10, after which the strip is rolled up into substantially circular form with its ends adjacent but not meeting, as shown in Fig. 4.

In certain cases, as for example where the diameter of the arbor closely approaches that of the bore of the grinding wheel, I prefer to form the adapter as shown in Fig. 7. The device of Fig. 7 consists of a strip 10' rolled up as before described, to form a split ring but the fingers 11' are formed by striking 85 in parts of the body of the strip.

In each case, however, the adapter consists of a split ring, preferably of thin quadrangular cross section, with a series of fingers thereon at angularly spaced intervals. Each such finger is integrally connected at one end to the ring and extends inside the ring and longitudinally thereof.

The material used is preferably spring metal, which may be hardened and tempered after the adapter has been formed. The split ring part is constructed so that when compressed until its ends meet, it will readily fit into the bore 12 of a grinding wheel 13. The ring, when released, expands and presses 100

against the wall of bore 12 to frictionally hold the adapter in place. The fingers are preferably arranged so that they may be flexed within reasonable limits, whereby an adapter of one size will readily accommodate 5 arbors of several different diameters.

As an illustrative example, the bore 12 of wheel 13 may be one inch and, with that bore, I may use any of the three adapters shown in Figs. 5, 6 and 7. That shown in Fig. 5 will accommodate arbors having diameters from one-quarter of an inch to three-eighths of an inch, both inclusive. That shown in Fig. 6 will accommodate arbors 10 having diameters from seven-sixteenths of an inch to five-eighths of an inch, both inclusive. That shown in Fig. 7 will accommodate arbors from eleven-sixteenths of an inch to seven-eighths of an inch. The above 15 figures are purely illustrative and not intended in any sense as limits.

It will be noted that in Figs. 5, 6 and 7, the intermediate one of the three fingers 11 is not located exactly between the other two. The reason for this will appear from Fig. 4, 20 where the four fingers are shown with reference to a dotted circle 17, which may be taken as representing an arbor. The split ring 10 is not concentric with circle 17 until 25 it has been contracted to the diameter of bore 10. Consequently, the inner ends of the several fingers are not equidistant from the center of circle 17 and the two left hand fingers appear considerably out of center. 30 When ring 10 is contracted so that its outside diameter equals the inside diameter of bore 12, the inner ends of the several fingers are equidistant from the center of the ring, 35 which is then of true circular form.

40 In use, an adapter, of the proper size for the arbor to be used, is placed in the bore 12 of wheel 13, as above described, after which the arbor 14 is pushed into place. The spring fingers 11, even with the smallest 45 size of arbor in the range for which they are intended to be used, will be flexed radially outwards to some extent when the arbor is inserted and these fingers, being originally uniformly bent, will locate the shaft 50 centrally of bore 12 and will also frictionally hold it in place while the wheel 13 is being clamped between the usual flanges 15 by turning up nut 16. The fingers, it is true, 55 centralize the shaft merely at one point in its length but this is all that is required. The flanges 15, when drawn up against opposite faces of wheel 13, serve to square up the shaft and force its axis into parallelism with that of bore 12. Therefore, it is simply necessary to center the shaft at one point only.

Because of this fact, a single adapter is all that is necessary for each wheel, whether that wheel be wide or narrow. Therefore, 60 I can make the adapter of a width to suit

the narrowest wheel used and it will then serve for wheels of all other widths.

Since the wheel 13 is clamped between the flanges 15, it is unnecessary that the adapter do more than centralize the shaft. It does not have to be constructed to resist displacement of the shaft after the flanges have been applied. Consequently, it can be made of thin metal, permitting economy in manufacture. Also, one adapter is all that is required for each wheel. Moreover, as above described, the manufacturer needs to stock only the three sizes of adapters to satisfy the needs of all of his trade.

It will be obvious that the adapter will serve equally well for polishing, buffing and other sorts of wheels. The reference to grinding wheels is intended as an illustrative example of one of many possible uses for the invention and not in any sense as exclusive of such uses.

The invention has been disclosed herein, in an embodiment at present preferred, for illustrative purposes; but the scope of the invention is defined by the appended claim 90 rather than by the foregoing description.

What I claim is:

The combination with a grinding wheel and an arbor on which it is to be mounted, said wheel having a bore extending axially therethrough and larger in diameter than the arbor, of a single member located entirely within said bore and frictionally held to the wall thereof, a series of spring fingers on said member angularly spaced thereabout and directly engaging said arbor for centering it in the bore preliminary to clamping the wheel to the arbor, flanges for engaging opposite end faces of said wheel, and means for clamping said wheel between said flanges.

In testimony whereof I have affixed my signature.

ARCHIE D. ROBINSON.
